UNITED STATES PATENT OFFICE

WILLIAM C. HUEBNER, OF CHICAGO, ILLINOIS

FILM HOLDER

Application filed October 11, 1930. Serial No. 438,012.

This invention relates to improvements in film holders.

In the art of photo composing or photographic printing, the use of flexible films in lieu of glass, is constantly increasing. In certain classes of work, particularly labels, post cards and the like, the size of the subjects to be printed onto the press plates, is relatively small with a consequent increase in the number of holders required for the different films used for composing on a large press plate, if the work is to be done in the most expeditious and economical manner.

One object of my invention, therefore, is to provide an efficient, light and relatively inexpensive holder for films, which holder is especially adapted for use in photographic printing machines or photo composers.

Another object of my invention is to provide a film holder of the type indicated, having simple means for effecting localized stretching of the film and maintaining the film in its proper stretched and registered position with reference to the holder.

A still further object of the invention is to provide a film holder of the type indicated wherein are employed a plurality of attaching and stretching blocks, preferably of wood, which blocks may be manufactured in quantity at small expense and readily renewed or replaced.

Other objects of the invention will more clearly appear from the description and claims hereinafter following.

In the drawings forming a part of this specification, Figure 1 is a top plan view of a film holder having my improvements incorporated therein, part being shown in section to illustrate certain details of construction.

Figure 2 is an end elevation of the holder shown in Figure 1. And Figure 3 is an enlarged vertical, sectional view corresponding to the section line 3-3 of Figure 1.

In said drawings, the holder is shown as comprising a main frame A; a plurality of

attaching blocks B-B; carriers C-C for the respective blocks; and adjusting screws D-D for the blocks.

The holder A is preferably of open rectangular formation and may be made of wood or other suitable material and of any desired size, it being understood that the same will be built of substantial construction so as to always retain its rigidity. Along the inside edges of the frame A is secured a metal strip 10 of U-section, as best shown in Figure 3, said strip 10 having a lower flange 11, vertically extending web 12 and top horizontal flange 13 extended outwardly or away from the center opening of the frame, said flange 13 being spaced an appreciable distance above the upper surface of the frame A proper for the purpose hereinafter described. Said strip 10 may be secured to the frame A proper by any suitable means such as the tacks or other fastening devices 14. Inasmuch as the holder is to be used on a photo composing or photographic printing machine, the same must necessarily occupy a predetermined registered position and location thereon and must also be adapted for registering the film E thereon when in a registering device. For this purpose, the frame A is provided with means cooperable with corresponding registering means of the registering device and machine proper which, in the instance shown, comprises two discs 15-15 on the underside of the frame A and secured thereto, each of said discs having a dowel hole 16-16 adapted to fit and register with corresponding dowel pins of a registering device or support on the composing machine proper. As will be understood by those skilled in the art, the dowel holes 16 are accurately located and positioned so as to insure proper registry of the subject on the film.

On each of the sides of the frame A are a plurality of carriers C, there being three on each of the long sides and two on each

of the short sides, as shown in the drawings, although the number may be varied to suit different conditions and sizes of holders. Each of said carriers C, as best shown in Figure 3, preferably comprises a metal plate having a lower horizontal flange 17, vertical web 18 and top flange 19, the latter terminating at its inner edge in a downturned lip 20 for the purpose hereinafter described.

10 The carriers are adjustable toward and from the opening of the frame A by any suitable means, such as the bolt screws D, each of which has a swiveled connection with its respective carrier and the threaded shank thereof cooperable with a threaded plate 21 secured flush within the side edge of the frame A, as shown best by the sectional view in Figure 1. By this arrangement, it is evident that not only is the carrier C adjustable lineally toward and from the opening of the frame but also that the carrier is adapted to have a certain amount of angular movement relative to the frame A because of its loose swiveled connection with the screw bolt 25 D. In this manner, the carrier is given the desired lineal and pivotal movement essential for stretching the film in a very simple and cheap manner.

Each of the attaching blocks B is preferably made of wood or other suitable material for receiving tacks or staples, such as indicated at 22, for securing the edge of the film E thereto. Each block B is further of such vertical dimension that it is slidably guided and confined between the frame A proper and the flange 13 of the strip 10. To facilitate its removable attachment to its carrier, each block B will have a longitudinally extending groove 23 therein to receive, 40 endwise, the corresponding lip 20 of the carrier. In this manner, the block is movable inwardly and outwardly to correspond with the inward and outward movements of the carrier. To prevent accidental relative longitudinal shift between each carrier and its respective block, the latter may be temporarily held by a suitable tack or other fastening device 24, as indicated in Figure 3.

With the construction shown, it will be seen that the film E lies on top of the flange 13 and that the securing staples or other fastening devices are below the surface of the film and that there is no projecting part elsewhere on the holder above the film E, so 55 that the latter when on the holder, may be placed against a sensitized press plate and exposed under pressure as by vacuum, without danger of scratching or marring the photographic coating on the press plate.

60 In applying the film, the latter is tacked or stapled around all of its edges to the several blocks and the film is then stretched taut by individually adjusting the several blocks, during which operation the image on the film 65 will be registered in the registering device,

as understood by those skilled in the art. During this localized stretching of the film, it is evident that the blocks B may adjust themselves angularly within reasonable limits to conform to the stretching and giving of 70 the film.

By making the blocks B in the manner indicated and attaching them to the carriers, as shown, said blocks may be made by first forming a long strip of the wood with the proper 75 cross section and groove 23 therein and thereafter cutting the strip to the desired lengths of the blocks, thus providing a very economical replaceable attaching block.

The film holder hereinbefore described may 80 be made very light so as to facilitate handling and, because of its relatively inexpensive construction, a large number of them may be used economically in any plant so that a large number of individual films may be attached 85 to the holders and thus expedite the registering of the films on the holders and the use of the holders in the photo composing machine.

The film holder herein disclosed has been 90 described with particular reference for use with photo composers or photographic printing machines wherein pressure, generally a vacuum, is maintained between the film and the photographic print receiving surface during exposure, but I am aware that the film may be employed in other types of machines for making press plates wherein neither light nor pressure is employed in reproducing the 95 subject image from the film onto the press plate. 100

Although I have herein shown and described what I now consider the preferred manner of carrying out my invention, the same is merely illustrative and I contemplate all changes and modifications that come within the scope of the claims appended here-to. 105

I claim:

1. In a film holder, the combination with 110 an open frame; of a plurality of film attaching blocks mounted on said frame on the several sides thereof; and means for individually adjusting said blocks on the frame toward and from the opening.

2. In a film holder, the combination with 115 an open frame; of a plurality of film attaching blocks of material adapted to receive and retain fastening devices, said blocks being adjustably mounted on the frame; and means for individually adjusting said blocks on the frame toward and from the opening thereof.

3. In a film holder, the combination with 120 an open frame; of a plurality of carriers carried on said frame; means for individually adjusting the carriers toward and from the opening of the frame; and film attaching blocks removably secured to the respective carriers.

4. In a film holder, the combination with 125

an open frame having register means thereon cooperable with corresponding registering means of a registering device; of a plurality of film attaching blocks mounted on said frame around the sides thereof; and means for individually adjusting said blocks on the frame.

5. In a film holder, the combination with an open frame; of a plurality of film attaching blocks carried by said frame; and means for individually lineally adjusting said blocks on the frame, said means providing also for relative angular movement between the blocks and the frame.

10 6. In a film holder, the combination with an open rectangular frame; of a plurality of film attaching blocks movably mounted on the several sides of said frame, each of said blocks being adapted to receive a temporary 70 film securing device; and screw adjusting means cooperably associated with each of said blocks and the frame for effecting adjustment of the blocks toward and from the opening of the frame.

15 7. In a film holder, the combination with an open rectangular frame; of a plurality of film attaching blocks movably mounted on the several sides of said frame, each of said blocks being adapted to receive a temporary 75 film securing device; and screw adjusting means cooperably associated with each of said blocks and the frame for effecting adjustment of the blocks toward and from the opening of the frame, said means including 80 a loose swiveled connection permitting angular movement of each block with respect to the frame.

20 8. In a film holder, the combination with an open rectangular frame; of a channel shaped strip secured around the inside edge 85 of the frame, said strip having a supporting flange spaced from the frame proper and against which the film is adapted to be seated; a plurality of film attaching blocks slidably 90 mounted on the frame and between it and said flange; and means for adjusting the blocks toward and from the opening of the frame.

25 9. In a film holder, the combination with an open frame; of a plurality of wood film attaching blocks mounted on said frame on the several sides thereof; and means for individually adjusting said blocks on the frame toward and from the opening.

30 10. In a film holder, the combination with an open frame; of a plurality of carriers mounted on said frame; means for individually adjusting the carriers toward and from the opening of the frame, said means providing also for relative angular movement between the carriers and the frame; and replaceable wood film attaching blocks secured to the carriers.

35 11. In a film holder for use on a photographic printing machine, the combination

with an open frame; of register means on said frame adapted to cooperate with corresponding registering means of a related photographic printing apparatus; a plurality of blocks mounted on the frame to which the 70 edges of the film are adapted to be secured; and means for adjusting the blocks inwardly and outwardly with reference to the center of the frame.

In witness that I claim the foregoing I 75 have hereunto subscribed my name this 30th day of September, 1930.

WILLIAM C. HUEBNER.
